UNITED STATES PATENT OFFICE.

WALTER W. BOUGHTON, OF DENVER, COLORADO, ASSIGNOR, BY MESNE ASSIGNMENTS,
TO COMMUNITY MAUSOLEUM ASSOCIATION, A CORPORATION OF COLORADO.

MAUSOLEUM.

1,333,602.

Specification of Letters Patent. Patented Mar. 16, 1920.

Application filed February 4, 1918. Serial No. 215,395.

To all whom it may concern:

Be it known that I, WALTER W. BOUGHTON, a citizen of the United States, and a resident of the city and county of Denver, State of Colorado, have invented a certain new and useful Improvement in Mausoleums, of which the following is a full, clear, and exact description.

My invention is an improvement in mausoleums and more particularly in what are known as "community" mausoleums in which there are incorporated a very considerable number of crypts in a single structure. The principal object of my invention is the provision of a structure of the class mentioned in which provision is made for thorough and complete disinfection of escaping gases, in which the individual crypts may be hermetically sealed after the period of decomposition is completely over, and withal in which the arrangement is such that space in the structure is utilized in the provision of a maximum number of crypts for a structure of a given size. A further object of my invention is the provision of a structure in which the disinfectant holding traps are so located that they may be filled from the main corridor without the necessity of entering a crypt and even, if desired, after a casket has been deposited in the crypt. Further and more detailed objects and advantages of my invention will later appear in this specification.

In the two sheets of drawings accompanying this application and forming a part hereof—

Figure 1 is a transverse vertical section through one wing of a mausoleum constructed according to my invention, illustrating the preferred arrangement of parts;

Fig. 2 is a partial vertical section and partial elevation, showing on an enlarged scale the disinfectant containing U and the means for ultimately sealing of the crypt; and

Fig. 3 is a partial end elevation of a wall between two crypts, the disinfectant holding U tubes appearing in dotted lines.

Referring to the drawings, in which like characters of reference designate like parts in the several views, 1 indicates the foundation of the mausoleum and 2 the floor beams carried thereon a sufficient distance above the ground to leave a space 3 connected with the outer air by a suitable number of ventilators 4. 5 are the side walls of the main

structure, which are covered with a facing 6 and in which there are provided a suitable number of grilles 7, 8 communicating between the outer air and the space 9 between the crypts and the wall 5. A roof 10 covers the structure and leaves a space 11 above the upper crypts which space communicates with 9 and is closed from the corridor 12 by some suitable ornamentation 13. The individual crypts are designated by the numeral 14 and are located in tiers, each crypt being closed by bottom, side, top, and rear end walls. A removable front wall 15 is provided, this front wall being a slab which is adapted to be sealed in place after an interment.

In order to comply with sanitary regulations, which require thorough disinfecting of gases which escape from such structures, it is customary to provide a body of disinfecting liquid usually contained in a U-shaped trap, through which all escaping gases must pass. These traps have heretofore, so far as I am aware, been located in the rear wall of the crypts, thus necessitating the provision of a passageway at the rear of the crypts (in place of the narrow air space 9), this passage being required for the filling of the U traps at the time of use and for the manipulation of certain valves, etc. The reason that the traps cannot be filled at the time of building the structure is that the disinfecting liquid is volatile and as some of the crypts at least may not be used for a period of a great many years, it is not feasible to fill the traps until such time as the crypt is to be put to use. Neither can they be safely filled from within the crypt before use especially if the filling opening is at the rear of the crypt on account of the volatile and poisonous nature of the disinfectant. Charging of the U-trap should therefore take place after or just previous to the act of sealing the crypt.

In my construction the mouth 16 of the U-shaped trap 17 containing the disinfectant 18 opens from the side wall M of the crypt very close to the front wall 15; so near that the trap may be filled from the main corridor even after a casket C has been placed in the crypt. Since the trap is embedded in a side wall its plane lies at right angles to the filling aperture and an elbow must be formed at 19. In one of the limbs of the U trap I provide a seat 20 for a ball valve 110

21 which normally closes the passage against the outward flow of gases.

5 In the event of an excess pressure of gases below the valve it will be lifted for their escape through the second **U** 22 into the vertical vent pipe 23 which communicates with space 11 or, as shown, with both spaces 3 and 11, from either of which exit into the open air is free through the plurality of 10 vents provided therefor. A screw plug 24 forms a means for inserting the ball 21 and then closing the **U** trap.

15 While the ball 21 forms a very reliable means of shutting off all entrance to the crypt, it is desirable to provide means whereby the crypt may be positively sealed at all points after the period of evolution of gases has certainly passed. I have provided means in the short **U** 22 for effecting such 20 sealing. The reference numeral 25 indicates a plurality of small balls of very low fusing metal which are placed in the **U** 22. These balls in their original condition do not interfere with the exit of the gases which pass 25 freely through the interstices between them. In the walls of the **U** 22, but preferably insulated therefrom, there are provided a pair of electrical contacts 26, 27 to which are joined the wires 28, 29, leading out through 30 the wall M to its front face where a pair of contacts therefor 30, 31 are provided.

35 The manner of use of the invention described will be obvious from the foregoing. After a casket C has been deposited in its crypt the disinfecting solution 18, which may be formaldehyde or the like, may be introduced into the mouth 16 of the trap as by pouring from a can having a long necked spout. Then the front slab 15 will be set 40 and sealed in place. Now the only opening into the crypt is 16 and the disinfectant fumes pass over from this filling the crypt and aiding in reducing decomposition. Loss of the formaldehyde by evaporation 45 into the atmosphere is prevented by the ball 21. If the gas pressure in the crypt becomes very high some of these gases will pass out through the disinfectant and raise the ball 21 from its seat; the excess above that 50 pressure which will allow the ball to gravitate back to its seat will escape through the vent pipe 23 and then the ball will reseat itself.

55 After the expiration of a considerable length of time, when it becomes certain that all decomposition which evolves gas has ceased, if it is desired to hermetically seal the crypt, a source of current is connected to the contacts 30, 31 and passed through the 60 mass of balls 25 from one contact 26 to the other contact 27. These balls being of low fusing, relatively high resistance metal will be fused down in sufficient quantity to close the **U** 22 when the metal has solidified.

Now when the current has been shut off the metal will set and close the **U** 22 hermetically. It will, of course, be obvious that if desired to conceal the presence of the contacts 30, 31 in the wall M suitable ornamentation may be employed to this end, and that 70 other changes in details and arrangements may be made without departing from my invention. I do not, therefore, desire to be considered as limited to the precise embodiment shown further than is indicated by 75 the appended claims.

Having thus described my invention, what I claim and desire to secure by Letters Patent is:

1. A ventilating appliance for mausoleums 80 comprising a trap having an outlet for gases, a conduit connected with the outlet, a fusible substance in said conduit having interstices for the passage of gases, and means for causing an electric current to pass through the 85 substance to close its said interstices by fusion.

2. A ventilating appliance for mausoleums comprising a trap having an outlet for gases, 90 a conduit connected with the outlet, a mass of fusible balls in said conduit, and means for causing an electric current to pass through the balls to fuse them together and thereby hermetically seal the conduit.

3. A ventilating appliance for mausoleums 95 comprising a trap having an outlet for gases, a conduit connected with the outlet, a fusible substance in said conduit, having interstices for the passage of gases, and means remote 100 from the trap for causing an electric current to pass through the substance to close its said interstices by fusion.

4. A ventilating appliance for mausoleums comprising a trap having an outlet, a conduit connected with the outlet, a fusible substance in said conduit having interstices for the passage of gases, electrodes in said connection and means remote from the trap for causing an electric current to pass between 105 said electrodes, through said substance to 110 close its said interstices by fusion.

5. A ventilating appliance for mausoleums comprising a trap having an outlet for gases, a **U**-shaped conduit connected with the outlet, a mass of fusible balls in said conduit, 115 and means for causing an electric current to pass through the balls to fuse them together and thereby hermetically seal the conduit.

6. A ventilating appliance for mausoleums comprising a trap communicating with the atmosphere, means adapted to hermetically seal the communication between the trap and the atmosphere by electrical action, a circuit for said means, and a controlling medium in the circuit. 120

In testimony whereof I have hereunto affixed my signature.

WALTER W. BOUGHTON.
